UNITED STATES PATENT OFFICE.

CARL BLECHER, OF BERLIN-DAHLEM, GERMANY.

PROCESS FOR INTAGLIO-PRINTING.

1,250,421.

Specification of Letters Patent. Patented Dec. 18, 1917.

Application filed May 22, 1915. Serial No. 29,890.

To all whom it may concern:

Be it known that I, CARL BLECHER, a subject of the King of Prussia, residing at Berlin-Dahlem, in the Kingdom of Prussia, German Empire, have invented a new and useful Process for Intaglio-Printing, of which the following is a specification.

This invention relates to a process for preparing printing surfaces for intaglio printing on high speed printing presses and has for its primary object to reduce to a minimum the amount of time required for carrying out a process of this nature. For this purpose, the text and illustrations which are to be reproduced, are preferably etched simultaneously and the use of a protecting band of lacquer of more or less breadth for sharply defining the edges of the pictures, done away with. A great saving of time thereby results, especially when cylindrical forms are employed.

In order to etch text and illustrations simultaneously, theoretically, it would be necessary to have the gelatin relief of the text ground higher than that of the highest lights of the pictures, for only in this way can the highest lights of the pictures be etched to the required degree without etching the ground of the text which is not permissible before the picture etching has been completed. Theoretically, the same conditions are involved in dispensing with the lacquer band for sharply defining the pictures. Thus, if the pictures on the printing surface are surrounded by a gelatin relief which is higher than the relief in the highest lights of said pictures and if said surrounding relief is sharply defined from the pictures (as required by the prints), it is possible, when the difference in relief between the highest lights and their surroundings is properly proportioned, to obtain the first etching of all shades of the pictures which are sharply defined from a colorless surrounding. The solution of this double problem depends upon the fact that the relief on the surface of the cylinder or plate etches through less when it is higher. The present invention contemplates such a relief formation on the cylinder or plate for the purpose of preparing the intaglio-printing surface containing text and illustrations by employing a diapositive with certain qualities. The process is thus carried out in the quickest manner possible.

In the drawings,

Figure 1 is a view in plan of a diapositive made according to the present invention;

Fig. 2 is a diagrammatic transverse section of a pigment negative relief on an enlarged scale.

According to Fig. 1 of the drawings, a diapositive is made from text and illustrations in any suitable manner, e. g., by means of a dry plate. The text having been printed on white paper, it, together with the illustration is mounted on white cardboard. A negative is made therefrom from which in turn the diapositive is taken. Said diapositive contains the text upon a ground 2 which is as transparent as possible, the picture being arranged within the free spaces in proportionally the same size and form in which they are to show up in the reproduction. This diapositive containing text and illustrations is a very thin sheet of gelatin or celluloid or other substance provided on one side with a light-sensitive coating having light portions 3 and shadow portions 4, and is treated on the light-sensitive coating side by covering the surface except the illustration, with an asphalt lacquer. Or if the non-picture side is treated, its surface is first covered with glue, celluloid or the like and after drying, all of the surface outside of the illustration is covered with the lacquer. Then the diapositive is placed in a solution of coal-tar or other non-actinic dye, the entire diapositive being thus prepared for hindering the transmission of light to any suitable degree. After this the lacquer is washed off. The purpose of this treatment is to make it possible to copy the diapositive containing text and illustrations upon the plate or cylinder in a manner which without any further treatment shows a relief which is proportional to the non-actinic dye of the pictures, the highest lights of the illustrations being less in relief than the text ground.

Referring now to Fig. 2, the negative relief comprises fully transparent portions *a* and *b* corresponding respectively to the empty space between illustration and text and the space surrounding the text, and the high light portion *c* which hinders the transmission of light due to the non-actinic dye with which it has been treated. It will be seen therefore that that part of the diapositive which carries the illustration, is colored

with a red or brown tone. The pigment negative relief is copied under such a dia-positive and then etched, the parts *a* and *b* in Fig. 2 are those parts which have been placed under the uncolored parts of the dia-positive which were previously covered with lacquer. The original surface of the relief negative is indicated by the dotted line in Fig. 2, the etching depths varying in different places corresponding to the tone of color on the dia-positive.

In order to effect the dyeing within the coat of the illustrations, all parts of the dia-positive outside of the illustrations are first coated with asphalt lacquer or the like, the contours of the pictures being observed exactly. The lacquered dia-positive is then placed for a certain length of time in a suitable solution such *e. g.*, as red coal tar dye in some instances or potassium permanganate in other instances. The coat of the dia-positive has absorbed certain quantities of the coal tar dye which produces a suitable brown under the influence of the solution of potassium permanganate. The colors thus obtained are therefore light-absorbing. The lacquer is washed off after drying the dia-positive.

In order to effect the dyeing outside the coat of illustrations, the combined dia-positive is first covered with celluloid, glue or the like; the dried coat outside of the illus-

trations being covered with asphalt lacquer while exactly observing the contours of the illustrations. The coat is then dyed by placing the dia-positive in aqueous or alcoholic solutions of *e. g.* red coal tar dye after which the lacquer is washed off. By thus introducing coal tar dye into the celluloid, glue or other coat, the light is suitably softened.

What I claim is:—

1. The process for preparing printing surfaces for intaglio printing, which process consists in preparing a dia-positive with text and illustrations and in treating that part of the dia-positive which corresponds to the illustrations to reduce the power of said part to transmit light therethrough.

2. The process of preparing intaglio printing surfaces, which process consists in preparing a dia-positive with text and illustrations, in coloring that part of said dia-positive which corresponds to said illustrations to reduce the power of said part to permit light to pass therethrough.

In testimony whereof I have hereunto set my hand in presence of two subscribing witnesses.

CARL BLECHER.
